Specification for Design.

Patented Nov. 7, 1911.

Application filed August 4, 1911. Serial No. 642,414. Term of patent 3½ years.

To all whom it may concern:

Be it known that I, HULBERT A. YERKES, a citizen of the United States, and a resident of the city, county, and State of New York, (whose post-office address is 154 Nassau street, New York city, New York,) have invented a new, original, and ornamental Design for Cabinets for Talking-Machines, which design is fully set forth in the annexed drawings, in which—

Figure 1 is a front elevation, and Fig. 2 a side elevation, of a cabinet embodying my invention.

I claim:

The ornamental design for a cabinet for talking-machines, as shown.

In testimony whereof I have signed this specification in the presence of two subscribing witnesses.

HULBERT A. YERKES.
